UNITED STATES PATENT OFFICE.

JAMES F. SMITHS, OF ZIONSVILLE, PENNSYLVANIA.

FLY-NET.

SPECIFICATION forming part of Letters Patent No. 249,112, dated November 1, 1881.

Application filed August 26, 1881. (No model.)

To all whom it may concern:

Be it known that I, JAMES F. SMITHS, of Zionsville, Lehigh county, Pennsylvania, have invented a new and useful Improvement in Fly-
5 Nets for Horses, of which the following is a specification.

This invention relates to that class of fly-nets shown and described in Letters Patent No. 237,622, which were granted to me February
10 8, 1881; and it consists of lashing the straps of leather together in such manner that each
15 lash passes through two holes in each strap and twice across the face of each strap under a loop formed of the lash, which reaches from
hole to hole and parallel with the length of the straps, whereby the net is made more durable
20 and to present a nicer appearance than heretofore.

Reference is to be had to the accompanying
25 drawings, forming part of this specification, in which similar letters of reference indicate corresponding parts in the figures.

Figure 1 is a face view of a portion of netting, showing my improved manner of lashing; and Fig. 2 is a view showing the appearance
25 of the back of the net.

The lashes B, which tie the straps or ribs of leather A together, are passed through the holes
30 a a of the straps or ribs, so as to form the bends b b, which pass from the back of the straps around the edges thereof, and across the faces of the straps in opposite directions, and so as to form the loops d, which reach from hole to hole over the bends b b, as shown. This manner of lashing the straps may be accomplished
35 in several ways. The method I prefer, how-

ever, is to begin, say, with the middle rib of the net and first pass both ends of the lash through the holes a a from the face to the back of the strap, and then carry the ends of the 40 lash over or around the edges of the strap and pass them in opposite directions through or under the loop d. The ends of the lash are now ready to tie the other straps on both sides of the center or middle strap. In successively 45 tying these side straps I first place the lash across the face of the strap to form the loop d; then pass it around the lower edge of the strap, and then through one of the holes a from the back of the strap to the face; then 50 over that portion of the lash d which was laid across the face of the strap, and then through the other hole from face to back; then over the upper edge of the strap, and thence, finally, down through or under the loop d. 55

Instead of beginning with the middle rib of the net, the tying may begin with the side ribs or straps, in which case the last-described method should be followed throughout.

Having thus described my invention, I claim 60 as new and desire to secure by Letters Patent—

In a fly-net for horses, the combination, with the leather straps A, of the lashes B, each passing through two holes, a a, of each strap, to form the bends b, and thence around the edges 65 in opposite directions across the face of the strap, to form the loops d, extending from hole to hole, as described.

JAMES F. SMITHS.
